SEWING MACHINE

Carl W. Johnson, Brooklyn, N. Y., assignor to
 American Machine and Foundry Company, a
 corporation of New Jersey

Application September 7, 1940, Serial No. 355,738

28 Claims. (Cl. 112—171)

This invention relates to a sewing machine and more particularly to sewing machines of the under and over stitch type in which the ends of a double pointed needle are alternately grasped by needle bars and projected back and forth through the work as it is moved into the range of action of the needle.

The invention relates generally to improvements in a machine of the type shown in my co-pending application, Serial No. 289,907, filed August 12, 1939, for Sewing machine, and has as its chief object the provision of improved co-acting elements which will increase the general efficiency of the sewing machine and its scope of use.

It is an added object of my invention to provide an improved sewing machine having a tension finger arranged to coact with the reciprocating needle on the thread adjacent the eye of the needle, and move it out of the path of the needle so that likelihood of the thread being engaged by the point of the needle is materially lessened.

It is a further object of my invention to provide an improved thread guiding device which acts as a medium for allowing the thread to be moved by the tension finger out of the path of the needle.

My invention also consists in the provision of improved driving mechanism which is localized in one general position to the rear of the machine so that there is more room available at the front of the machine for sewing instrumentalities and also the several driving gears employed are kept clear of lint and thread, thereby resulting in a more efficient and compact structure.

I have also provided thread guides for improving the movement of the thread so that it is always guided to proper position relative to the traveling thread puller and out of the path of the thread being pulled by said thread puller.

It is also an object of my invention to provide improved mechanism operating beneath the work support of the machine for tensioning the thread and moving it out of the path of the needle as it moves down through the support, and to provide also means for adjusting the amount of tension applied.

According to my invention the thread is under tension at all times and properly positioned relative to the needle. In order to prevent excess tension being imposed upon the thread as it forms the stitches and puckering the work, I have provided improved means for gripping the thread beneath the work support prior to

the operation of the thread puller and means forming a part of the gripping device for allowing the thread to be moved clear of the path of the needle.

5 A further object of my invention is to provide a pair of improved gripper arms which will aid in proper positioning of the thread in the cut-out portion around the periphery of a drum.

An additional object of my invention is to 10 provide a simplified and more direct means for operating the needle chucks in timed relationship.

Another object of my invention is to provide a 15 simplified, faster operating and smoother drive for a thread puller arm.

My invention also consists in an improved arrangement of the thread receiving drum which will allow additional room for the operator's legs and hence adds to the general efficiency in the 20 operation of the machine.

With these and other objects not specifically mentioned in view, the invention consists in certain combinations and constructions which will be hereinafter fully described, and then set forth 25 in the claims hereunto appended.

In the accompanying drawings, which form a part of this specification, and wherein the several reference characters designate the same or like elements:

30 Fig. 1 is a side view, partly in section, of a portion of the improved sewing machine;

Fig. 2 is a front elevation, taken from line 2—2 of Fig. 1, the handwheel and needle bar cam being omitted to more clearly illustrate the driving means;

Fig. 3 is an enlarged detail view taken from line 3—3 of Fig. 1, showing the upper needle bar, the material feeding arm and its co-acting feed foot and presser foot;

Fig. 4 is a detail view illustrating the mounting of the looper arm and tension finger as seen from line 4—4 of Fig. 3;

Fig. 5 is a detail view showing a portion of one 45 of the needle bars and the connection to its cam actuated lever;

Fig. 6 is a detail view taken from line 6—6 of Fig. 5;

Fig. 7 is an enlarged sectional view of the 50 improved needle bar in needle receiving position;

Fig. 8 is a view of a needle bar, partly in section, showing a needle grasped by the needle bar chuck;

Fig. 9 is a partial sectional view of a part of 55 the needle bar showing the needle as it is about

to be transferred from one needle bar chuck to the other;

Fig. 9a is an enlarged detail view of a portion of a modified needle bar equipped with a removable inert providing means for the use of different size needles;

Fig. 10 is an enlarged partial view of a round grooved needle adapted for use with the needle bar chuck;

Figure 20 is a partial assembly view partly in section showing the relationship between the needle, needle actuating bars and other thread handling mechanisms; and

Figure 21 is a diagrammatic perspective view showing the coaction between the needle bars, looper, and tension fingers during the operation of the latter.

Referring to Fig. 1, the sewing machine, which is of the same general type as that shown in copending application, Serial No. 289,907, filed August 12, 1939, by Carl W. Johnson for Sewing machines, consists of a center support frame 30 and a combination end frame and housing 31, the frames being secured to and spaced by supporting member 32 which in turn are secured to the pedestal 33 of the machine as shown in Fig. 2. The frame 30 supports a bracket 34 carrying the forward end of the sewing machine table 35, the rear end of the same being secured to spaced blocks 36 which are fastened to the frame 31.

A pulley 37 is driven by a belt 38 which also runs over a pulley (not shown) integral with a clutch mechanism driven from a motor (not shown) in the same manner as disclosed in the copending application referred to above. Therefore, the drive as well as the mechanism for operating the clutch and a brake is omitted in the present case.

Pulley 37 is secured to the hub 40 of a gear 41 rotating about a stationary stud 42 fastened to the wall of frame 31 by screws 43. A handwheel 44 secured to pulley 37 is provided to permit manual turning of the machine. A cam 39 cooperates and rotates with pulley 37. This cam may be formed as a separate member; or as in the present application, it may be formed integral with and on the inside face of pulley 37. Cam 39 is provided with a cam track 45 engaging cam followers 46 and 47 positioned at diametrically opposite points of the cam, these followers being carried by the extending arms 48 and 49 at the rearward end of their respective oscillating levers 50 and 51. The levers 50 and 51 are pivotally mounted on shafts 52 and 53, respectively, shaft 52 being supported at one end in a hub 54 of a bracket 55 secured to the wall of member 31 and its other end being supported in a lug 56 extending from the bridge 57 of member 31. One end of shaft 53 is supported in a hub 58 of

a bracket 59 fastened to the wall of member 31; its other end is supported in a hub 60 of a bracket 61 attached to a support 62 fastened to member 31 as shown in Figs. 1, 13 and 14. An upper needle bar 63 and a lower needle bar 64 (Figs. 1, 3 and 14) arranged in axial alignment are provided with actuator members 65 connecting to extending arms 66 and 67 at the forward end of their respective oscillating levers 50 and 51 whereby to convert the oscillating motion of said levers into a vertical reciprocating motion of the needle bars. The upper needle bar 63 is guided in bushings 68 and 69 carried by lugs 70 projecting from the forward end 71 of bridge 57 (Figs. 1 and 3). The lower needle bar 64 (Fig. 14) is guided in bushings 72 and 73 carried by lugs 74 extending from support 62.

The actuator members 65 heretofore mentioned are held in place on their respective needle bars 63 and 64 by lock nuts 75 as seen in Figs. 5 and 6. The vertical extending portion 76 of members 65 is provided with a track 77 in which slides a rectangular block 78 inserted on the end of a stud 79 fixed in the end of arms 66 and 67. The sliding block 78 permits means for converting the oscillating motion of arms 66 and 67 into a vertical reciprocating motion of the needle bars 63 and 64. The member 65 of the upper needle bar has an extension 80 (Figs. 5 and 6) provided to perform an operation to be described presently.

This machine has a double pointed needle having a point at each end, and an eye about midway of its length through which the thread passes. This needle is used in conjunction with the improved needle bars 63 and 64. Since both needle bars are constructed in the same manner, like reference numerals will be used to designate like parts, and only one will be described.

Referring to Figs. 7 and 8, the upper needle bar 63 as shown may consist of an outer shell 85 which at its upper end has a threaded portion receiving a plug 86, having an aperture 87 slightly larger than the diameter of the operating rod 88. Rod 88 at its lower end is provided with a plug portion 89 fitting into an aperture 90 of the inner shell 91 which is held against a shoulder 92 of rod 88 by means of a pin 93. The combined rod 88 and shell 91 are guided in aperture 87 of the plug 86 and in the aperture 94 of shell 85. The shell 91, at its lower end is provided with a seat 95 adapted to serve as a stop for the base of the cage or ball retainer portion 96 of a slidable plug 97 guided in the aperture 90 of shell 91. The plug 97 is normally held in the position shown in Fig. 7, abutting the seat 95 by a compression spring 98.

The lower portion of shell 85 is equipped with a stud 99, Fig. 9, the same being held in place by a split wire ring 100 fitting into an annular groove 101 in shell 85 and in the open end slots 102 provided in stud 99, thereby providing a means for quick and easy removal for cleaning and replacement. The stud 99 is provided with an opening 103 formed to suit the point of the needle and serves to stop the needles at the same position each time it is transferred from one needle bar to the other.

It will be understood by those skilled in the art that in this type of machine the needle 81 is alternately grasped by the jaws of each needle bar. The action is such that as the lower needle bar 64 advances the needle inwardly through the work, it passes through the opening 104 in the lower end of shell 91 of the upper needle bar

63, and openings 105 in the cage 96 and stops against stud 99 in the opening 103 as seen in Figs. 7 and 9. The upper and lower needle bars 63 and 64 are identical in construction and operate in the same manner for gripping and releasing the needle in projecting the same back and forth through the work so that the operation of only one needle bar need be described in detail. During the transfer period, shell 91 comes to rest because of the engagement of shock absorber 111 with a bushing 68. At the same time, shell 85 of the lower needle bar 64 connected to arm 67 continues its upward movement relative to the cage 96 of plug 97, then resting against stop portion 95 of shell 91 so that due to this relative movement, tapered portion 107 of shell 85 moves away from rollers 106 to release and grip on the lower end of the needle held thereby. The round needle 81 may be provided with grooves 108, Fig. 10, thereby providing better means for the balls 106 to properly obtain a firmer grip on the needle.

With the needle in position, the oscillating lever 50, previously mentioned, carries the shell 85 of the needle bar 63 upward, whereby the balls 106 become wedged between the needle 81 and the tapered wall 107 thus firmly gripping the needle, at the same time, the gripping balls of the lower needle bar are released and the continued ascent of shell 85 causes the needle 81 and ball retainer plug 97 also to rise, as seen in Fig. 8. When the eye 82 of the needle 81 is in a position close to the base of shell 91, the stud 99 carried by shell 85 which has ascended freely in an elongated slot 109 in shell 91 held stationary with respect to shell 85 until shock absorber 111 is lifted from bushing 68, abuts the upper end of the slot 109, and the travel of shell 85 effects the movement of the several parts of the needle bar unit (as shown in dotted lines in Figure 8) thereby carrying the needle through the work. By supporting approximately half the length of the needle, the possibilities of breaking or flexing of the same is greatly reduced during subsequent operations presently to be described.

A spring 110 is confined in the aperture 94 of shell 85 and normally tends to hold a shock absorber 111 made of rubber or any other suitable material, which may be integral with a knurled nut 112 on rod 88, against the face of bushing 68. The tension of spring 110 is great enough to overcome the tension of spring 98 which therefore causes the latter to be compressed (Fig. 8) during the needle gripping and positioning operation heretofore mentioned.

The upper needle bar 63 descends as a unit until the shock absorber 111 abuts the face of bushing 68 and arrests the travel of rod 88 and its coating shell 91. The shell 85 and plug 97 continue their downward travel and finally the base of the cage 96 abuts its seat 95 stopping the travel of plug 97 but the shell 85 continues downward slightly, as indicated by the dotted lines in Fig. 7, thus releasing the gripper balls 106 freeing the needle. It is understood that the needle has passed through the work and entered into the lower needle bar 64 and is being gripped by the latter in the manner that the upper needle bar accomplishes the same. The movement of rod 88 and shell 91 of the lower needle bar unit is controlled in the same manner as the upper needle bar, that is the rod 88 carries a shock absorber 111 which abuts the face of the lower bushing 73 as seen in Fig. 14.

The nut 112, on rods 88, provides means for

adjusting the gripping elements 106-107 of each needle bar (Figs. 7 and 8). When properly adjusted, nuts 112 are held in place by lock nuts 113. In transferring the needle from one needle bar to the other, both shells 85, for a short distance travel in unison, that is one moves to release the needle and stops, while the opposing one grips the needle and continues its travel to carry the needle through the work.

10 Referring to Fig. 9a, means are shown whereby the needle bars can easily and quickly be adapted to receive different size needles. The base of sleeve 91 may be provided with a tapped hole 115 to receive a threaded insert or bushing 116 having an opening 117 which is slightly larger than the diameter of the needle to be used. If a needle of larger or smaller diameter is desired, member 116 can be readily removed and replaced by a like member having an opening to accommodate the new needle. The openings 105 in the cage 96 are large enough to accommodate the maximum size needle.

A presser foot 120 (Figs. 1 and 3), used in conjunction with a feeding foot 121 and a feed plate 122 attached to a cam actuated arm 123, is provided to engage and retain the work in position during the sewing operation. The presser foot 120 is clamped to the lower end of a rod 124 guided in the upper and lower lugs 70 of member 71. The upper end of rod 124 supports a bar 125 which is clamped between lock nuts 126 and supports one end of the tension springs 127 which connect to the upturned ends 128 of a plate 129 fastened to the upper lug 70. The springs 127 normally tend to hold foot 120 in work position and since the bar 125 can be moved up and down on the rod 124, the tension of the springs 127 can be adjusted so as to exert the desired pressure of the foot to suit different types of work.

40 A block 130 which is clamped on rod 124 supports one end of a link 131 connecting to a lever 132 loosely mounted on a stud 133 carried by an arm 134 which in turn is fastened to the bar portion 135 of a rod 136. The vertical extending

45 arm of lever 132 supports an arm 137 connecting to a crank 138 of a rotating shaft 139 whereby an up and down motion is imparted to the presser foot 120 and the feeding foot 121 which is attached to the bar 135. The upper end of rod 136 is guided in a swivel block 140 and may be equipped with trunnions 141 mounted in open end slots 142 provided in the supporting member 143 which also carries flat springs 144 adapted to engage and hold the trunnions 141 in position.

55 Bar portion 135 of rod 136 is guided in a slot 145 provided in the lower lug 70 of member 71, said lug also having tapped holes 146 to receive screws which hold a guide plate (not shown) in place. A plate 147 attached to the lugs 70, is provided with an elongated slot 148 which guides the movement of the arm 134. Shaft 139 (Figs. 1, 2 and 3) is rotated by a gear 150 in mesh with an intermediate gear 151 driven by the main gear 41. Gear 151 is mounted on a stud 152 supported by the end wall of housing 31.

To facilitate the starting of new work, and also permit the operator to inspect the work at intervals during sewing operations, presser foot 120 and feed foot 121 are so arranged that they 70 may be lifted whenever the operator desires. This feature is accomplished by providing a knee plate 153 (Fig. 1) which is adjustably fastened to a rod 154 by a thumb screw 155, the upper end of rod 154 connecting to a head 156 clamped to a cross shaft 157. Shaft 157 at one end is piv-

totally mounted in a bearing of support 32 and its other end mounted in a bearing of a bracket 158 fastened to the support 62. An arm 159 is fixed to shaft 157, and coacts with a bar 160 slideable in a vertical track 161 provided in housing 31, the upper end of the bar 160 engaging a pin 162 projecting from an arm 163. (Figs. 1 and 2) mounted on a shaft 164 supported by members 31 and 57. The opposite end of shaft 164 is equipped with a hook shaped finger 165 (Figs. 1 and 3) adapted to engage the bottom of a collar 166 secured to rod 124. When the knee plate 153 is moved in the direction indicated by the arrow, it lifts the bar 160 causing the arm 163 to turn shaft 164 whereby the finger 165 engages collar 166 and lifts the presser foot 120 and through its connections will also lift feed foot 121. A tension spring 167 (Fig. 1) stretched between a post 168 of arm 159 and a post 169 carried by member 62 tends to reset the unit.

A looper cam 170 (Figs. 1 and 2) engages a cam roller 171 which is mounted on a stud 172 carried by a lever 173 fastened on a cross shaft 174. The cam roller 171 is held in engagement with cam 170 by means of a spring 175 which is stretched between a post 176 in lever 173 and a post 177 in a lug 178 extending from housing 31. Shaft 174 at one end is supported by housing 31 and its other end in a hub 179 of a bracket 180 (Fig. 3) secured to the face 71 of bridge 57.

A looper arm 181 (Figs. 3 and 4) secured to shaft 174 at its lower end is provided with a pointed finger 182 and a thread guide roller 183 which, together with a tension finger 184 act upon the thread in a manner hereinafter to be described. The finger 184 is secured to an arm 185 loosely mounted on shaft 174, the hub of arm 185 being mounted between fibre washers 186 serving to maintain frictional contact with looper arm 181, the frictional means being maintained by the pressure of a compression spring 187 placed between a collar 188 fastened to shaft 174 and a collar 189 loose on the shaft. The finger 184 is normally held inoperative by a stop screw 190 adapted to engage a pin 191 projecting from arm 185, screw 190 being adjustably fastened in a wing 192 of a holder 193 fastened to 71. When the needle is transferred from the lower needle bar 64 to the upper needle bar 63, the latter grasps the needle and ascends by means of the cam actuated lever 50 to its up-position. The looper arm 181, by means of its cam 170, is moved toward finger 184 as soon as the needle bar 63 has ascended sufficiently to permit it to pass, arm 181 continuing to travel until its pointed finger 182 is about in alignment with the tip of finger 184, in which position it momentarily dwells. The needle bar then descends slightly and dwells and in so doing a loop is formed in the thread and substantially simultaneously arm 181 and finger 184 advance in unison, and arm 181 engages the front loop of the thread while finger 184 engages the rear loop of the thread, both members continue advancing and pulling the thread, for reasons to be described hereinafter. The advance of finger 184 is stopped when pin 191 abuts the wing 194 of holder 193, while arm 181 completes its full swing and carries the thread as shown in Fig. 17. Arm 181 immediately starts to retreat whereupon needle bar 63 descends and in so doing the extension 80 of its actuator member 65 engages the curved surface 195 of finger 184, causing the same to be returned to its starting position, as shown in Fig. 3. The needle bar 63 and arm 181 complete their

travel and return to the positions shown in Fig. 3, it being understood that in the meantime the needle has passed through the work and is now gripped in the lower needle bar 64, while bar 63, looper 181 and finger 184 retain their positions until the needle is again transferred to the upper needle bar.

With needle 81 gripped in the lower needle bar 64, it descends by means of its cam actuated lever 51 to down position at the same time pulling the thread partly through the work, whereupon it immediately ascends slightly and dwells, this slight upward movement tending to form a loop in the thread. At this time a pair of cam actuated gripper arms 200 and 201 (Figs. 11, 13 and 14) close around the needle and the looped portion of the thread to prevent unnecessary pulling of the stitch as a thread puller 202 enters the front loop of the thread and starts to completely pull the free end of the thread through the work as seen in Figs. 15 and 18.

The gripper arms 200 and 201 are operated by a cam 203 adjustably attached to a cam 204 secured to a shaft 205. Cam 203 (Figs. 1 and 11) has a cam track 199 engaging a cam follower 206 of a cam lever 207 mounted on a stud 208 carried by a holder 209 fastened on a support 210 attached to frame 30. The upper end of cam lever 207 is provided with an open end slot 211 adapted to engage a pin 212 in a bar 213 sliding in a runway 214 of a block 215 secured to member 62. Since the bar 213 operates the gripper arms 200 and 201 in the same manner as in the co-pending application heretofore referred to, a more detailed showing of the same is deemed unnecessary.

The bar 213 when moved in one direction causes the arms 200 and 201 to close about the needle 81 and the looped portion of the thread and retain this position while the thread puller 202 engages the thread and advances it about the periphery of a drum. When the bar 213 is moved in the opposite direction, arms 200 and 201 return to their open position permitting the lower needle bar 64 to be moved upward.

The cam 204 is provided with a flange 216 and a shoulder 217 slightly smaller in diameter, adapted to receive the cam 203, said cam 204 also having at its end another flange 218 and shoulder 219 to receive a cam 220. With the cams 203 and 220 properly set to fulfill their duty in timed relation with cam 204, they are clamped in position by means of bolts 221. The cam shaft 205 is supported at one end thereof in a bearing 222 of housing 31 (Fig. 1) and its other end in a bearing 223 of a stationary drum 224 secured to supports 225 attached to frame 30 as seen in Figs. 1 and 11. Shaft 205 is equipped with a gear 226 in mesh with an intermediate gear 227, mounted on a stud 228 supported by the wall of housing 31 (Figs. 1 and 2), which in turn is driven by the main gear 41.

The gear 226 drives an intermediate gear 229 mounted on a stud 230 which meshes with a gear 231 integral with a gear 232 mounted on a stud 233 which is supported in a bearing 234 of housing 31. Gear 232 drives a gear 235 (Fig. 2) mounted on a shaft 236 which is supported in a hub of a bracket 237 secured to frame 30. The shaft 236 imparts motion to the material feed arm 123 (Fig. 3) in the same manner as disclosed in the co-pending application heretofore mentioned; therefore a showing of the same is omitted in the present case.

Gear 232 (Figs. 1 and 2) carries spaced bars

240 and 241 forming a runway or track 242 engaging a roller 243 of an arm 244 which is clamped on one end of a shaft 245 supported by member 210; the opposite end of shaft 245 carries an arm 246 which at its upper end is provided with the thread puller 202. The motion imparted to arm 246 and its thread puller 202 by crank arm 244 is such that as the puller 202 advances its forward pointed end to engage the loop formed in the thread, as seen in Figs. 15 and 16, it moves slowly and engages the front loop of the thread and starts to pull the thread entirely through the work. Therefore the puller 202 does not act with such quickness in starting the pull of the thread through the work with a tendency to fray out the thread after a number of pulls or with a tendency to jerk and break the same but after the pull is started, the puller gradually increases speed when danger of thread breakage is past. The action of the thread puller, therefore, is to pull the loose end of the thread through the work with gradually increasing speed from approximately the time it first picks up the thread until it approaches the pick-up position, whereupon its advancing facility is gradually retarded.

Coating with the thread puller, needle and needle bars, and acting to tension the thread properly and also prevent fouling of the thread or splitting by the needle, is a finger 247 (Fig. 13), which in the illustrated embodiment is provided with a hook at its free end and engaging and pulling the thread out of the path of the needle as it moves back and forth through the work. At the time of transfer of the needle from one needle bar to the other, the thread is held out of the position of the needle so that the thread is always clear of the needle and properly tensioned.

The motion of this finger is controlled by cams 248 and 249 (Fig. 12) secured to a vertical shaft 250 supported in a hub 251 of a bracket 252 fastened to the drum 224 (Fig. 1). The lower end of shaft 250 is equipped with a spiral gear 253 in mesh with a spiral gear 254 fixed on the cam shaft 205 (Figs. 1 and 11). Cam 248 (Fig. 12) engages a cam follower 255 of an arm 256 loosely mounted on a stud 257 carried by a lug 258 of bracket 252, the other end of arm 256 supporting a link 259 connecting to an arm 260 which is attached to the lower end of a stud 261 (Fig. 11) loosely mounted in a hub 262 of a lever 263. The stud 261 (Figs. 11 and 12) terminates in a head 264 in which is adjustably clamped the finger 247 receiving oscillating motion from link 259 having an elongated slot 265 in which moves a stud 266 on arm 260. An adjusting screw 327 permits the finger 247 to be set in any desired position in order to engage the thread properly. A spring 267 is connected to arm 260 and has its other end attached to an adjustable rod 325 which allows spring 267 to be tightened or loosened by turning nut 326 located at the end of said rod for varying the amount of tension to be applied by finger 247.

Stud 266 is normally held by spring 267 in the position shown in Fig. 12 but can travel in slot 265 in order to tension the thread or prevent damage to the machine should any obstruction appear. Should spring 267 break or be rendered inoperative for any reason which might cause finger 247 to be located in the path of needle 81, stud 266 will be engaged by the far end of the slot 265 as lever 256 swings in a clockwise direction on stud 257 (Figure 12) and finger 247 will be moved clear

of the needle path and avoid having the needle ram into finger 247.

The cam 249 engages a cam roller 268 of an arm 269 which is integral with lever 263 loosely mounted on a stud 270 carried by lug 258, this cam importing somewhat of a closed or four-motion path of movement of the tension finger 247. A tension spring 271, stretched between posts 272 and 273 carried by lever 263 and arm 256, respectively, is provided to hold the cam followers 255 and 268 in engagement with their cam.

The finger 247 operates in conjunction with a guide plate 275 fastened to a throat plate 276 (Figs. 13 and 14) guide plate 275 being provided with an opening 277 which is shaped more or less like a key slot. The opening 277 tends to guide the thread within the path of the finger 247 which may describe a path of movement corresponding somewhat to the contour of the opening and in so doing the hooked end of the finger 247 moves to engage the thread and pull the same laterally to one side of the needle thereby moving it out of the needle path, and holding the thread in that position, while the needle reciprocates, and then moves back to re-engage the thread on the next stitch.

The throat plate 276 is attached at its forward end to bracket 34 and its opposite end is supported by a spacer 278 (Fig. 1) carried by member 215. Plate 276 is provided with a fill-in plate 279 (Fig. 13) and two similar plates (not shown) which are provided with slots to permit movement of the material feed members and also movement of the thread. The above mentioned plates are omitted in order to more clearly show the feed members 121 and 122 and the guide plate 275.

The cam 204 (Fig. 11) is provided with a cam track 280 engaging a cam roller 281 of a trip arm 282 mounted on a stud 283 carried by a lug 284 of member 215. The upper end of arm 282 engages the end of a plug 285 which is secured to the end of a spring tensioned rod 286 which terminates in a member 287 having a vertical extending jaw portion 288. The pointed part 289 of a swinging arm 290 together with jaw portion 288 form a jaw adapted to clamp the thread and later carry the same upward to fulfill a duty presently to be described. The plug 285 and rod 286 slide in suitable apertures provided in arm 290 and a spring 291 confined in the aperture of the arm tending to normally hold the plug 285 against the end of arm 282. The swinging motion of arm 290 is accomplished by cam 220 having a cam track 292 engaging a cam roller 293 of a cam lever 294 loosely mounted on a stud 295 carried by a lug 296 (Fig. 1) of member 62. Lever 294 at its upper end supports a head 297 (Fig. 11) carrying a rod 298 connecting to a depending arm 299 of arm 290 which is mounted on a stud 300 carried by member 215.

The operation of the stitching of the work will now be described. With the needle 81 grasped by the lower needle bar 64 (Fig. 15), the needle bar descends its full stroke through the work, and immediately ascends slightly and dwells, the slight upward motion forming a loop L in the thread T. At this time the cam actuated gripper arms 200 and 201 (Fig. 19) close around the needle and the looped portion of the thread, to prevent unnecessary pulling of the stitch in the work as the thread puller 202 (Fig. 15) enters the front loop of the thread and starts to pull the free end F of the thread through the work. As the puller 202 travels in a clockwise direction the front loop of the thread is caused to move along the tapered

portion 301 which directs the thread into the groove 302 of the puller, whereby the thread is placed over a ledge 303 of the gripper arm 200 as seen in Figs. 11 and 19. It will be noted that the vertical plane passing through the center of the drum is disposed to one side of the needle path to give the operator more room beneath the sewing machine. Ledge 303 assists in the movement of the thread and makes it possible to guide the thread laterally and direct it more easily down onto the drum. With the thread partly around the groove 302 which may be cut at an angle, as seen in Fig. 19, the thread is caused to be placed against the edge 304 of the pointed portion 305 (Fig. 11) of a stationary guide member 306 attached to member 215 as seen in Fig. 11, the edge 304 aligns the thread so as to pass through the space between jaws 288 and 289 (Fig. 11). As the puller 202 advances, the jaws 288 and 289 begin to close and when the puller reaches a position about as seen in Fig. 16, the jaws clamp the thread as seen in Fig. 19, the thread being still clamped by arms 200 and 201. The thread A in the meantime is guided onto a shelf 307 of a drum member 308 which is bolted to a member 309 as seen in Figs. 15, 16 and 17. As the puller advances it positions the thread B in a groove 310 of member 309 and continues moving and completely pulls the free end F through the work at which time the arms 200 and 201 open, permitting the lower needle bar 64 to ascent. The operation of the thread puller is similar to that in my above referred to application in that it moves at a slow speed into engagement with the looped thread in order not to break the thread, then accelerates and moves more rapidly to complete the operation of pulling the loose end of the thread through the work. The clamped jaws 288 and 289 swing upwardly in unison with the ascent of the needle bar 64 and in so doing the thread A is caused to enter into a trap 311 of the stationary guide member 306 (Fig. 11), the finger 247 (Figs. 11 and 13), engaging the thread and pulling it out of the path of the needle and holding it there until the upper needle bar ascends.

The ascent of jaws 288 and 289 causes the thread A to be moved from shelf 307 laterally and disposed in trap 311 in a manner similar to that set forth in my copending application mentioned above. With the needle grasped by the upper needle bar 63, the same ascends its full stroke and immediately descends slightly forming a loop in the thread and dwells. Shortly before the ascent of the needle, the jaws 288 and 289 open, permitting the needle to pull a portion of the free end of the thread through slot 314. The arm 181 and finger 184 now move inwardly in unison and the finger 182 of arm 181 engages the front thread F of the loop and pulls the thread through slot 314, the arm advancing to a position shown in Fig. 17, finger 184 engaging the rear thread of the loop and moving to a position shown in Fig. 17. In this position, the thread overlies the hooked portion of the finger thereby relieving the tension of the thread passing through the eye of the needle. Arm 181 immediately starts to retreat, whereupon needle bar 63 descends and in so doing the extension 80 (Fig. 3) of actuator member 65 engages the curved portion 195 of finger 184 causing the same to be returned to its starting position as seen in Figs. 3 and 16. The jaws 288 and 289 start descending with the descent of needle bar 63 and are returned to their starting position. The tension finger 247 (Fig. 13) engages the thread and

moves it out of the path of the needle 81 as it descends to perform its stitch and be transferred to the opposite needle bar.

Before each transfer of the needle, the feed arm 122 and feed foot 121 advance the work one stitch length. The presser foot 120 at such time is raised sufficiently to permit the work to be moved, when the material feed reaches the end of its stroke the presser foot descends clamping the work against the work table and the arm 122 descends slightly and returns to its starting position at which time it is again raised to engage the work. The feed foot 121 is advanced by the material feed arm 122 and when the latter descends, the feed foot, by means of its mechanism heretofore described, is raised permitting a spring actuated arm 316 (Fig. 3) to return it to the starting position. Arm 316 is loosely mounted on a stud 317 carried by a lug 318 extending from bridge 57, a spring 319 coiled about the hub of arm 316 having one end arrested in a hole in lug 318 and its other end passing through a hole provided in the arm.

It is to be understood that the form of my invention, herewith shown and described, is to be taken as a preferred example of the same, and that various changes in the shape, size and arrangement of parts may be resorted to, without departing from the spirit of my invention, or the scope of the subjoined claims.

What is claimed is:

1. In a sewing machine of the class described, the combination with alternately moving needle bars, of a needle, means for alternately connecting said needle with said bars for projection with a thread through work to be sewed, means for moving the thread out of the path of movement of said needle including a finger arranged to engage said thread, a support for said finger, and means for moving said support to move said finger in a substantially closed path substantially at right angles across the path of movement of said needle into and out of thread engaging position.

2. In a sewing machine of the class described, the combination with a pair of aligned alternately operating needle bars, of a needle, mechanism for reciprocating said bars to alternately connect said needle with said bars for projecting said needle and a thread back and forth through material to be sewed, a support, an arm mounting said support for movement, a finger carried by said support, and driving means co-acting with said support and operating in advance of the movement of said needle to move said finger at substantially right angles across the path of said needle into and out of thread engaging position.

3. In a sewing machine of the under and over type stitch, a tensioning device for preventing fouling of the thread by the needle, comprising a support, a finger mounted on said support, mechanism for moving said support to move said finger in a closed continuous path into engagement with the thread to tension it in the work, including means for moving said finger into contact with the thread when the needle is transferred from one needle bar to another, means for maintaining said finger in tensioning relationship, and means for withdrawing said finger from engagement with said thread following the conclusion of the formation of a stitch.

4. A thread tensioning device comprising a support, a finger arranged to engage said thread, and mechanism for moving said finger cyclically in a

closed path into and out of tensioning relationship with said thread, including means for maintaining said finger in engagement with said thread during a portion of each stitch forming cycle, said last-named means also including means for moving said finger out of engagement with said thread.

5. A thread tensioning device for a sewing machine, comprising a table, a thread guide formed in said table, a traveling support mounted beneath said table and guide, a finger mounted on said support and arranged to engage said thread, and means for moving said support to move said finger relative to said guide in a closed path to tension said thread and maintain it out of the path of a needle.

6. A thread tensioning device for a sewing machine having opposed needle bars and a needle which is projected back and forth with a thread through material to be sewed, comprising a support, a shaft mounting said support, a tension finger carried by said support, and projectable into position to engage said thread, a support actuating arm, a finger actuating lever, a second finger actuating lever, a link connecting said levers, and cams coacting with said arm and said levers for moving said finger in a closed path into and out of thread engagement.

7. In a sewing machine a needle bar carrying a needle and thread for sewing, a work table having a thread guide formed in said table, and provided with an irregular opening, a tension finger located beneath said table, and means for moving said finger in a closed path conforming to the shape of said guide opening for tensioning and holding the thread out of the path of said needle.

8. In a sewing machine, a needle bar carrying a needle and a thread for sewing, a work table having an irregularly shaped thread guide formed therein, a tension finger located below said table and projecting into position adjacent said guide to engage said thread, and means for moving said finger to engage said thread to tension the same and move said thread in said opening out of the path of said needle.

9. In a sewing machine having a needle bar holding a needle and a thread for sewing, a work table having a thread guide provided with an opening formed therein, a tension finger provided with a thread engaging point located to engage said thread, means for mounting said finger for translatory movement of said thread conforming substantially to the shape of said opening in said guide, and means for maintaining said finger stationary during a part of each sewing cycle of said machine to position said thread out of the path of said needle.

10. In a sewing machine having a needle bar holding a needle and a thread for sewing, a tension finger provided with a thread engaging point located to engage said thread, means for mounting said finger for translatory thread engaging movement, and means for maintaining said finger stationary during a part of each sewing cycle of said machine to position said thread out of the path of said needle, said last-named means including means for moving said finger to free said thread from engagement with said finger.

11. In a sewing machine having a vertical operating needle and a work table, a thread displacing finger, and means for moving said finger in a substantially horizontal plane and in a closed path beneath said table to maintain a thread clear of the needle and to tension the thread during formation of the stitches.

12. In a sewing machine provided with a needle bar and a needle for projecting a thread through material to be sewed, a member movable in a substantially horizontal plane into and out of engagement with said thread, and mechanism for moving said member across the path of travel of said needle to pull said thread to tension it relative to the material and to hold it out of the path of said needle each time said needle is passed through the work.

13. In a sewing machine provided with a needle bar for projecting a needle and thread through work to be sewed, a work table arranged to support material to be sewed, said table being provided with a thread guide, a member located beneath said table and movable in substantially a horizontal plane for engaging said thread, and means for driving said member in timed relation to the movement of said needle to pull said thread laterally within the limits of said guide and maintain said thread out of the path of said needle during its movement through the work.

14. In a sewing machine having opposed needle chucks and a double pointed needle which is projected back and forth with a thread through material to be sewed, a yieldingly mounted thread guiding and tensioning device constructed to engage said thread, means for moving said device into engagement with said thread and for translating said thread after engagement therewith out of the path of movement of said needle and maintaining it clear of said needle, mechanism coacting with said device for properly tensioning said thread, and means for adjusting said mechanism to control the tension exerted thereby within given limits.

15. In a sewing machine having opposed needle chucks and a double pointed needle which is projected back and forth with a thread through material to be sewed, a yieldingly mounted thread guiding and tensioning device constructed to engage said thread, means for moving said device into engagement with said thread and for translating said thread after engagement therewith out of the path of movement of said needle and maintaining it clear of said needle, mechanism coacting with said device for properly tensioning said thread, and means for adjusting said mechanism to control the tension exerted thereby within given limits, said means including a spring actively associated with said device, a control member connected to said spring, and means for moving the control member relative to said spring to vary the tension exerted by said spring on said device.

16. In a sewing machine having opposed needle chucks and a double pointed needle projected back and forth with a thread through material to be sewed, a thread guiding and tensioning device, and means for moving said device at regular intervals in a closed path, part of said path passing through the range of movement of the needle for holding the thread clear of the needle and tensioning said thread.

17. In a sewing machine having opposed needle chucks and a double pointed needle projected back and forth with a thread through material to be sewed, a thread guiding and tensioning device, means for moving said device at regular intervals in a closed path, part of said path passing through the range of movement of the needle for holding the thread clear of the needle and tensioning said thread, and means for varying the position of said device relative to the thread to be engaged thereby.

18. In a sewing machine having opposed needle bars, a double pointed needle, means for moving said bars to project said needle back and forth with a thread through material to be sewed, a thread guiding and tensioning device, means for moving said device at regular intervals in a closed unidirectional path, part of said path passing through the range of movement of the needle for holding the thread clear of the needle and for tensioning the thread.
19. In a sewing machine of the under and over stitch type, the combination with a pair of alternately operating needle bars and a double pointed needle, of means for alternately connecting said needle with said bars for projecting a thread having a fixed and a loose end through material to be sewed, a pair of thread gripping jaws located adjacent one of said needle bars, one of said jaws being provided with a reduced thread guiding portion, means for operating said jaws to grip the thread against movement relative to said needle at the conclusion of the stitching operation, and means for pulling the loose end of said thread over said reduced portion of said jaw.
20. In a sewing machine of the class described, the combination with an upper and a lower alternately operating needle bar and a needle, of a pair of thread gripping jaws positioned adjacent said lower bar, a thread guide formed adjacent the end of one of said jaws, and means for closing said jaws in timed relation to said bar for gripping said thread.
21. In a sewing machine of the class described, the combination with a needle and a needle bar, of a thread receiving drum, said needle bar being located so as to move a needle in a path disposed to one side of the vertical plane passing through the center of said drum, a thread gripping member positioned adjacent said needle bar, and a thread guide formed adjacent the end of said gripping member.
22. In a sewing machine, a needle bar carrying a needle and a thread for sewing, the combination with a pair of gripper arms located adjacent said needle bar, one of said arms being provided with a cut-away portion, means for operating said arms to grip the needle and thread at the conclusion of the stitching cycle, and means for pulling the loose end of said thread past said cut-away portion.
23. In a sewing machine, a thread receiving drum and a thread puller comprising, a thread pulling member, a shaft, an arm mounting said thread puller fixed to said shaft, a crank arm mounted on said shaft, a roller mounted on said crank arm, a thread puller driving member, a track on said member engaging said roller, and means for driving said thread puller driving member to cause said track and roller to coast and rotate said puller at varying speeds.
24. The method of controlling a thread having a loose and a fixed end being projected through material by a needle in forming over and under stitches in said material which comprises moving a predetermined limited portion of said thread extending within the range of the path of movement of the needle laterally beneath the material and at substantially a right angle across the path of movement of said needle to locate said predetermined limited portion of said thread out of the path of movement of said needle, positively holding said engaged portion of said thread out of the path of the needle while the thread is being projected through the material to form a stitch and pulling the loose end of the thread through said material during the formation of each stitch.
25. The method of controlling the position of a thread being projected by a needle in a vertical plane back and forth through material to be sewed in forming over and under stitches which comprises moving said thread laterally with respect to said needle beneath said material and at substantially right angles across the path of said needle after it has been projected through said material to locate said thread out of the path of travel of said needle, and holding said thread beneath said material clear of the path of said needle, and applying tension thereto while said needle is again projected through said work to form another stitch.
26. The method of controlling a portion of a thread being projected through material by a needle in forming over and under stitches which comprises moving said portion of said thread laterally beneath said material and at substantially right angles across the path of said needle to dispose said portion of said thread out of the path of movement of said needle, and positively holding said portion of said thread out of the path of said needle while said needle is being projected through said material to form a stitch.
27. The method of controlling a thread being projected in one plane back and forth through material to be sewed in forming over and under stitches comprising engaging the thread beneath said material in a direction normal to said plane, moving said thread laterally beneath said material in a substantially horizontal plane to a position out of the path of movement of said needle and remote from the position where it was first engaged, holding said thread beneath said material at said remote position during a partial forming of a stitch, and then releasing said thread.
28. The method of controlling a thread being projected by a needle through material to be sewed in forming over and under stitches comprising translating a portion of said thread laterally beneath said material in a substantially horizontal plane away from the point of stitching and out of the path of travel of said needle, tensioning and holding said thread in said lateral position during a part of the stitching cycle, and then releasing said thread.

CARL W. JOHNSON.
